US00D994636S

(12) **United States Design Patent** (10) **Patent No.:** **US D994,636 S**
(45) **Date of Patent:** **** Aug. 8, 2023**

(54) **LOUDSPEAKER DOCK**

(71) Applicant: **Harman International Industries, Incorporated**, Northridge, CA (US)

(72) Inventors: **Kristopher Bellinghausen**, Whitmore Lake, MI (US); **David Dixon**, Livonia, MI (US); **Jeffery E. Fay**, Farmington Hills, MI (US); **Jose Tomas DeLuna**, Canton, MI (US); **Royce D. Channey**, Ann Arbor, MI (US)

(73) Assignee: **Harman International Industries, Incorporated**, Northridge, CA (US)

(**) Term: **15 Years**

(21) Appl. No.: **29/865,760**

(22) Filed: **Aug. 11, 2022**

Related U.S. Application Data

(63) Continuation of application No. 29/740,620, filed on Jul. 6, 2020, now Pat. No. Des. 964,311.

(57) **CLAIM**

The ornamental design for a loudspeaker dock, as shown and described.

DESCRIPTION

FIG. 1 is a top perspective view of a loudspeaker dock showing the new design;

FIG. 2 is a bottom perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top view thereof; and,

FIG. 8 is a bottom view thereof.

The broken lines in the figures illustrate portions of the loudspeaker dock that form no part of the claimed design.

1 Claim, 8 Drawing Sheets
